(57) **CLAIM**

The ornamental design for an accessory holder, as shown and described.

DESCRIPTION

FIG. 1 is a perspective view of an accessory holder as seen from the top, front and right sides;

FIG. 2 is a front elevational view thereof;

FIG. 3 is a side elevational view thereof;

FIG. 4 is a rear elevational view thereof;

FIG. 5 is an enlarged top plan view thereof;

FIG. 6 is an enlarged bottom plan view thereof;

FIG. 7 is a perspective view similar to FIG. 1 wherein the broken line work is for environmental purposes only and does not constitute a part of the claimed design; and

FIG. 8 is an enlarged fragmentary view of a portion of the design.

FIG. 9 is a fragmentary view of the hanging means for the accessory holder.

FIG. 10 is a view similar to FIG. 9 wherein the hanging means is a swiveling alternative embodiment; and,

FIG. 11 is a rear elevational view of the invention, similar to FIG. 4, where the loop member is removed portraying an alternative embodiment.
